UNITED STATES PATENT OFFICE.

ERIC HARRY LILJEBLADH, OF GOTTERNBOORG, SWEDEN.

SHEET-SEPARATING DEVICE FOR PAPER-FEEDING MACHINES.

Application filed January 21, 1926, Serial No. 82,806, and in Sweden December 7, 1925.

This invention relates to sheet separating devices in paper feeding machines for printing presses or similar appliances, by means of which a single sheet from a pile of paper 5 is separated from the pile and fed forwards to the printing press or machine, with which the feeding device is combined. More specifically the invention relates to such sheet separating apparatus, which are disposed at 10 the rear edge of the paper pile with respect to the feeding direction and the principal operating device of which comprises a suction foot.

One object of this invention is to provide 15 such means, that when the uppermost sheet is seized by the suction foot and raised by it, the front edge of said sheet is displaced neither forwards nor backwards by the lifting movement of the suction foot.

20 A further object of the invention is to provide means for disengaging the sheets from one another when ready for becoming seized by the suction foot.

Further objects of the invention are to 25 prevent the raising of more than one single sheet at each lifting movement of the suction foot and to properly hold the other sheets in the pile in proper position during the forward feeding of the uppermost sheet. 30 With these and other objects in view the invention consists in the combination of elements described in the accompanying specification and referred to in the appended claims.

35 In the accompanying drawings:

Figure 1 is a side elevation view of the apparatus with the suction foot resting on the paper pile,

40 Figure 2 is a similar elevation view with the suction foot raised having seized the uppermost sheet, whereby some parts are shown in section,

Figure 3 is a plan view of the apparatus,

45 Figure 4 shows the apparatus from beneath,

Figure 5 is an end view looking from behind,

Figure 6 is a side view of a portion of the improved device,

50 Figure 7 is a side elevation view of the assembled apparatus with driving elements, in a smaller scale, and

Figure 8 a detail of the suction foot in a side elevation, partially cut.

55 Similar numerals of reference are em-

ployed to indicate corresponding parts throughout the several figures of the drawings.

A main body 1, that holds all the parts of the apparatus together, is slidably 60 mounted on a main bar 2, which is substantially horizontally placed in the feeding direction of the sheets and secured in the proper position by a fastening screw 3 so as to be easily loosened by a simple grasp. 65 The main bar 2 has its forward end 20 by means of a link 78 secured to the printing press 71 or to the machine, to which the sheets are to be fed, and its rear end 200 is secured by a releasable clamping device 4 to a carrier 5. The screw 4 on the frame work 71, to which the apparatus is applied, goes through a vertical slot 6 in the carrier 5, so that the bar end 200 can if wanted be displaced in vertical direction 70 and secured in position by tightening the clamping screw 4.

On the main body 1 and in one piece therewith two guide bushes 7, 8 are provided for the steering each of a sliding 80 rod 10, 11 respectively, which sliding rods carry a suction foot holder 9. The bushes 7, 8 are, according for the purpose of this invention, given an inclination forwards 85 against the vertical line as shown in Figs. 1 and 2 and for the purpose, that will be more particularly described here below.

The suction foot holder 9 is formed as a fork, in the two shanks 12, 13 of which a suction foot 15 is pivotally mounted on two 90 horizontal journals 14 placed in right angle to the feeding direction. The one shank 13 of the holder 9 is provided with a slot 16, through which a set screw 17 passes, that is screwed into an ear 18 projecting from the 95 suction foot 15, to make it possible to vary the inclination of the suction foot with reference to the holder 9.

The intermediate portion 90 of the suction foot holder 9 is formed as a crank, the 100 pin 900 of which is gripped by the jawlike end 190 of the one arm 19 of a bell crank lever, that is pivotally mounted on the main body 1 by means of a pin 21. The other arm 22 of the said bell crank lever by means of a slotted bush 24 and a set screw 23 is clamped to a rocking rod 25, which is given a reciprocating movement by a crank 72 on an oscillating shaft 79 in the printing press 105 71.

The upper portion of the main body 1 above the pin 21, is formed as a low pressure air collector 26, the main pipe of which is designated by 27 and by a flexible tube 73 connected to a suction pump 74. The collector 26 is provided with two pipe sockets 28, which by flexible tubes 29 are connected each to a similar socket 30 on the suction foot 15, so that the cavity 31 of the suction foot 15 communicates through the collector 26 with the suction pump 74.

The collector 26 further is provided with an air sluice 32 to regulate the vacuum therein by allowing atmospheric air to enter the collector 26.

A distributor 34 for compressed air is bolted to the main body 1 by screws 33 behind the collector 26. The main pipe 35 of the distributor 34 is connected to a compressor pump 76 by a flexible tube 75. The distributor 34 at its lower end is provided with two pipe sockets 36 and at its upper portion with two other sockets 37. In the distributor 34 there is between these two pairs of sockets provided a throttle 38, the shaft 39 of which passes through the wall of the distributor 34 and is provided with a radially projecting arm 40, disposed in the way of a finger 41 secured to the sliding rod 10 on the suction foot holder 9. A spiral spring 41^a connected to the main body 1 tends to hold the throttle 38, normally closed.

According to the present embodiment of the invention the suction foot 15 is provided with an angular broken suction face, the front portion 42 of which is horizontal, and the rear portion 42^a directed upwardly in an acute angle towards the pile. Extending backwardly from the suction foot 15 lugs 43 project as a continuation of the inclined portion 42^a forming supports for two curved nozzles 44 for the spraying of compressed air from the distributor 34, which nozzles are pivotally secured to the supports 43, so that they can variably be inclined with reference to the suction foot 15 by means of set screws 45. The nozzles 44 are connected to the upper sockets 37 of the distributor 34 by flexible tubes 46.

The lower disposed pipe sockets 36 of the distributor 34 are connected to two other nozzles or air spraying heads 48 by flexible tubes 47, which heads 48 are situated so far abaft the suction foot 15, that their position is behind the rear edge of the pile 100, and they are adjustable up and down in vertically disposed holders 49, which holders are displaceable laterally being slidably mounted on a cross bar 50 positioned square to the feeding direction and secured to the main body 1 by means of set screws 500. The heads 48 are provided with bottoms, inclined forwardly and downwardly, as clearly shown in Fig. 1. In the front wall the heads 48 are provided each with a ver-

tical slot 51 as a nozzle for the jet of compressed air.

The main body 1 also carries a rearwardly directed bar 52, below and parallel to the main bar 2. Along the bar 52 a support 53 is slidable and provided with an upwardly directed forked guide 54, which slides along the main bar 2. Further an arm 55 projects downwardly from the support 53 forming a bearing pin 57, whereupon a flap 56 is hinged in such a way, that it can swing up and down in a vertical plane parallel to the feeding direction, whereby the pin 57 is positioned substantially in the same horizontal plane as the operative surface 42, when the suction foot 15 is in its lowermost position. The pin 57 has a crank 58, which carries a slotted bush 60 with a set screw 59, by which the bush 60 can be clamped to a rocking rod 61, that is given a reciprocating movement 85 from a crank 77 on the aforementioned oscillating shaft 79 in the printing press 71.

The flap 56 near its hub 56^a carries an upright standing bow 62 pivotally mounted to the flap 56 and surrounding the intermediate portion of the support 53. The bow 62 fits the front top portion 63 of the support 53, which has such a height and width, that the bow 62 when the flap 56 is raised can be moved upon the portion 63. To automatically cause this movement a spiral spring 64 is wound about the one pivot 65 of the bow 62 and secured at a pin 66, which is fixed somewhat higher on the bow 62, so that the tension of the spring 64 tends to cause the bow 62 to swing forwards. A stop pin 67 on the support 53 prevents the bow 62 to swing in too far above the portion 63. Another pin 68 is secured to the main body 1 in order to push down in a certain moment the bow 62 off the portion 63 for the purpose mentioned below. On the upper side of the flap 56 there is an adjustable stud 69, which in the raised position of the flap 56 strikes against the under side of the support 53 thereby limiting the raise of the flap 56. The support 53 also is provided with a spiral spring 70, the one end of which is secured to the main body 1 and which with a certain flexibility counteracts the rearward movement of the support 53.

The operation of the machine as thus described is as follows:

The paper pile 100 is placed in position on the table 110, whereupon the main bar 2, carrying the main body 1, is adjusted vertically by displacing its rear end 200 in the vertical slot 6 of the holder 5 and securing same in the desired position by the set screw 4. This adjusting is performed so far, that the suction foot 15 presses slightly against the paper pile 100 by means of the horizontal face portion 42. The set screws 3, 23 and 59 are now unscrewed and the whole apparatus pushed so far backwards, that the rear

edge of the suction foot 15 arrives only a little distance in front of the rear edge of the pile 100 as shown in Fig. 1, in which position the main body 1 is secured by tightening the screws 3, 23 and 59. The set screw 17 is now unscrewed and the suction foot 15 tilted about its journals 14, so that the portion 42 of its suction face is parallel with and gets a slight press against the pile 100. The suction foot is secured in this position, whereafter the air suction and air compressing pumps 74, 76 as well as the rocking rods 25, 61 and the driving mechanism are started.

The uppermost sheet of the pile will then be seized by the suction foot 15 and folded upwards against the rear portion 42^a thereof, the rear edge of the sheet falling outside the suction face against the extensions 43. During this suction period the valve 38 is open, the arm 40 pressed downwardly by the finger 41. In this position of the suction foot 15 compressed air streams through the both pairs of nozzles 44 and 48. The air from the nozzles 48, which is directed against the upper portion of the rear edge of the pile, will thereby loosen the sheets from each other in the said upper portion of the pile. The air from the nozzles 44, which is directed against the upper surface of the pile somewhat in line with the inclined suction face portion 42^a, tends to blow down such further sheets, which possibly are clinging to the uppermost sheet, when this is seized by the suction foot.

During this period the support 53 has been pushed by the rocking rod 61 into its most backward position, to be seen in Fig. 1, with the flap 56 raised, because the bow 62 in this position of the support 53 has been free to swing up on the portion 63 against the stop pin 67. The crank 58 is thereby inclined rearwardly and the adjustable screw 69 bears against the under side of the support 53.

The two rocking rods 25 and 61 now take in their most backward positions and in the next moment are given a forward movement. The rod 25 thereby turns the bell crank lever 22, 19 lifting the holder 9 with the suction foot 15 upwards, the movement of the latter guided by the sliding rods 10, 11 and bushes 7, 8. On account of the forward inclined position of the bushes 7, 8 mentioned above the lifting movement does not occur in a vertical direction but in a somewhat forwardly inclined direction. This inclination of the bushes 7, 8 is chosen so with reference to the inclined portion 42^a of the suction face, that the raising and folding motion of the uppermost sheet caused by the suction foot 15 does not displace the front edge of said sheet from its initial position. To accomplish this purpose exactly the upward motion of the suction foot might occur along a curved line instead of the straight line controlled

by the sliding rods 10, 11, but owing to the rather short length of the upgoing motion of the suction foot said curvature can be substituted by the said inclination of the rods 10, 11 without destroying the effect in any perceptible degree.

The finger 41 partakes in the upward movement of the sliding rod 10, whereby the arm 40 is released, so that the valve 38 is shut by the spring 41^a closing the air stream to the nozzles 48. On account hereof the compressed air in an increased quantity and thus with a higher tension will escape through the nozzles 44 and thus in a higher degree prevent any further sheet to follow the uppermost sheet when seized by the upwardly moving suction foot.

During the last mentioned period the rocking rod 61 moves forwardly the sliding support 53 with the flap 56 resting in the raised position by the bow 62, which still is disposed upon the portion 63. When the suction foot 15 is near the upper point of its stroke, the support 53 reaches its innermost position, whereby the pin 68 strikes against the bow 62 and pushes it rearwards down from the portion 63. The support 53 now will stop immovable yieldingly pressed against the rear end of the main body 1 by the spiral spring 70. The flap 56 however immediately drops down on the paper pile 100 against the now uppermost sheet, and prevents this sheet from being displaced during the feeding ahead of the sheet, which has been properly seized by the suction foot. Due to the manner in which the flap 56 is hinged on the pin 57 with reference to the upper surface of the pile 100, the front end of the same will drop down upon the pile with a substantially vertical movement, and hence displacement neither forwardly nor backwardly of that sheet in the pile, which gets touched by the dropping flap 56, will take place.

During the downward movement of the suction foot now following the rocking rod 61 has reached the forward point of its stroke and is given a backward movement. The arm 58 thereby at first moves backwardly turning the pin 57 in such a way, that the flap 56 is raised without displacing the support 53 out of its position, because of the action of the spring 70. Not earlier than when the screw 69 strikes against the under side of the support 53—in which position the flap 56 has totally lost its contact with the pile 100—the support 53 will be forced to follow the backward movement of the rocking rod 61, because then any further tilting of the flap 56 is impossible. The pin 68, which is stationarily fixed in the main body 1, once again permits the bow 62 to swing upon the portion 63 by the action of the spring 64, so that the flap 56 is prevented from not properly dropping down during

the next forward movement of the support 53.

The suction foot 15 now once again is in operative position on the pile 100, the sheet, 5 which now is the uppermost one, is seized thereto, the valve 38 is closed and the operation will be repeated in the way just described.

I do not limit myself to the constructional 10 embodiment of the invention described above and shown in the accompanying drawing, because slight variations in the parts can be found within the scope of the invention.

Having thus described my invention what 15 I claim is:

1. A sheet separating apparatus in paper feeding machines for the seizing of single sheets from a paper pile comprising a main body, an up and down movable suction foot, 20 forwardly inclined guides for said suction foot attached to said main body, said suction foot provided with an angular broken operative face, the front portion of which is substantially parallel to the feeding direction and the rear portion directed upwardly and continued by rearwardly projecting lugs, and means to move the suction foot straightlined up and down, said main body also provided with a distributor for 25 compressed air, connected with an air compressor, and with pairs of nozzles, one pair of which is pivotally mounted on the suction foot at the rear side thereof and the other pair of said nozzles mounted so far 30 abaft said suction foot, that the nozzles are disposed behind the pile of paper under operation.

2. A sheet separating apparatus in paper feeding machines for the seizing of single 35 sheets from a paper pile comprising a main body, an up and down movable suction foot, forwardly inclined straightlined guides for said suction foot attached to said main body, said suction foot provided with an angular 40 broken operative face, the front portion of which is substantially parallel to the feeding direction and the rear portion directed upwardly and continued by rearwardly projecting lugs, and means to move the suction foot up and down in said guides, said main body also provided with a distributor for 45 compressed air, connected with an air compressor, and with nozzles, so far abaft said suction foot, that the nozzles are disposed behind the pile of paper under operation, said distributor provided with a throttle for the 50 air supply to the nozzles, and means to shut said throttle, when the foot is raised, and to open same, when the suction is descended.

3. A sheet separating apparatus in paper feeding machines for the seizing of single 55 sheets from a paper pile comprising a main body, an up and down movable suction foot, forwardly inclined guides for said suction 60 foot attached to said main body, a flap

hinged on a sliding support behind the suction foot, means to reciprocate said support to and from the suction foot, means to hold said flap raised when said support moves from the suction foot, means to release the flap so as to permit it to fall down upon the pile of paper, when the support has arrived near to its front position and means to hold said support stationary during the raising and the dropping of said flap and means to adjustably limit the raising movement of the flap.

4. A sheet separating apparatus in paper feeding machines for seizing of single sheets from a paper pile comprising a main body positioned near the rear end of the pile, an up and down movable suction foot to grip the uppermost sheet near the rear end of the paper pile, forwardly inclined straightlined guides for said suction foot attached to said main body, and means to move the suction foot up and down in a forwardly inclined straightlined direction, whereby the foremost edge of the uppermost sheet rests unmovable during the lifting operation of the suction foot.

5. A sheet separating apparatus in paper feeding machines for the seizing of single sheets from a paper pile at the rear edge of the same comprising a main body, an up and down movable suction foot, forwardly inclined straightlined guides for said suction foot attached to said main body, said suction foot provided with an angularly broken operative face, the portions of which constituting plane surfaces, whereby the front portion is substantially parallel to the feeding direction and the rear portion directed upwardly, and means to move the suction foot up and down in a forwardly inclined straightlined direction.

6. A sheet separating apparatus in paper feeding machines for the seizing of single sheets from a paper pile comprising a main body, an up and down movable suction foot, forwardly inclined straightlined guides for said suction foot attached to said main body, a flap hinged on a sliding support behind the suction foot, means to reciprocate said support to and from the suction foot, means to hold said flap raised, when said support moves from the suction foot, means to release the flap so as to permit it to fall down upon the pile of paper, when the support has arrived near to its front position.

7. A sheet separating apparatus in paper feeding machines for the seizing of single sheets from a paper pile comprising a main body, an up and down movable suction foot, forwardly inclined straight lined guides for said suction foot attached to said main body, a flap hinged on a sliding support behind the suction foot, means to reciprocate said support to and from the suction foot, means to hold said flap raised, when said support

moves from the suction foot and means to adjustably limit the raising movement of the flap.

8. A sheet separating apparatus in paper feeding machines for the seizing of single sheets from a paper pile comprising a main body, an up and down movable suction foot, forwardly inclined straight lined guides for said suction foot attached to said main body,
- 5 a flap hinged on a sliding support behind the suction foot, means to reciprocate said support to and from the suction foot, means to hold said flap raised, when said support moves from the suction foot, means to release
- 10 the flap so as to permit it to fall down upon
- 15

the pile of paper, when the support has arrived near to its front position and means to hold said support stationary during the raising and the dropping of said flap.

9. In a sheet separating apparatus an angularly broken suction foot movable straightlined up and down, a hinged flap separated therefrom and pivotable about a centre disposed substantially in level with the horizontal portion of the operative surface of said broken suction foot when in the down position of said suction foot.

In testimony whereof I have affixed my signature.

ERIC HARRY LILJEBLADH.
